UNITED STATES PATENT OFFICE.

EDWARD J. DUGAN AND JOHN P. PANTE, OF MEMPHIS, TENNESSEE.

REVERSING MECHANISM FOR INTERNAL-COMBUSTION ENGINES.

1,237,314.

Specification of Letters Patent. Patented Aug. 21, 1917.

Application filed September 19, 1916. Serial No. 121,045.

To all whom it may concern:

Be it known that EDWARD J. DUGAN and JOHN P. PANTE, citizens of the United States, residing at Memphis, in the county of 5 Shelby and State of Tennessee, have invented new and useful Improvements in Reversing Mechanism for Internal-Combustion Engines, of which the following is a specification.

10 This invention relates to improvements in reversing mechanisms for internal combustion engines of the four cycle type.

The chief characteristic of this invention resides in the provision of a device of the 15 above described character in which the timing of the opening and closing of the valve is varied by means of cams which are movable axially of the cam shaft, the cam shaft being movable longitudinally to effect the 20 adjustment of the cams.

Another characteristic of this invention is to provide a device of the above described character having manually operated means for moving the shaft to effect the adjustment of the cam, and means associated with 25 the first mentioned means for temporarily breaking the ignition circuit upon the actuating of said cam shaft.

A further characteristic of this invention 30 is to provide a reversing mechanism in which a threaded means is interposed between the cam shaft and the cam to effect a predetermined movement of the cam upon moving the cam shaft longitudinally.

35 Other characteristics of the invention will appear as the specification is read in connection with the accompanying drawings, in which:—

Figure 1 is a side elevation of the device 40 showing the same applied to an internal combustion engine of the four cycle type, the internal combustion engine only being shown partly in section.

Fig. 2 is a longitudinal section of the 45 Fig. 1.

Fig. 3 is a transverse section taken on the line 3—3 of Fig. 1.

Fig. 4 is a detailed view of the circuit breaking mechanism.

50 Fig. 5 is a transverse section taken on the line 5—5 of Fig. 1.

Referring to the drawings in detail, our invention is shown in this instance applied to a crank case fully indicated as at A, 55 which has its opposite end wall provided with alined bearings 1 and in which is jour-

naled a cam shaft 2. The cam shaft 2 is of such a length as to have the opposite end thereof projecting beyond the opposite end of the crank case, the forward ends of the 60 cam shaft being rectangular shape in cross section as at 3, and upon which is slidably keyed a driving gear 4. To form a substantial support for the forward end 3 of the shaft 2, the crank case A has its forward 65 end provided with a substantially L shaped bracket 5 which has its upper end provided with a bearing 6 in which is journaled the outer end of the forward end 3. The gear 4 is adapted to be interposed between the 70 forward bearing 1 and the bearing 6 whereby longitudinal movement of the cam shaft may be had without moving the gear. The gear 4 is adapted to mesh with the gear mounted on the crank shaft whereby motion 75 may be imparted to the cam shaft 2 as will be understood. As means for rotating the cam shaft no way adds to the utility of this invention, it is thought that the showing of the same is unnecessary. 80

To avoid complexity of description we have shown only means for adjusting one cam upon the cam shaft although we wish it to be clearly understood that any number of cams may be simultaneously adjusted to 85 revert the rotation of the crank shaft without departing from the spirit and scope of the invention. Arranged within the crank case A are a pair of spaced uprights 7 which have their upper ends provided with the annular bearings 8, the cam shaft 2 being adapted to extend through the bearings as is clearly shown in the drawings. Keyed to the cam shaft 2 and journaled within the bearings 8 is a sleeve 9 which has its outer surface provided with spirally arranged threads 10, the sleeve being relatively longer to permit the wide adjustment of the cam as will be hereinafter described. Surrounding the sleeve 9 and interposed between the bearings 95 8 is a cam 11, the cam being of any suitable construction and having its inner surface provided with spirally arranged grooves 12, the grooves being adapted to receive the threads 10 whereby upon longitudinal movement of the sleeve, the cam will be rotated between the bearings 8. Arranged directly above the cam 11 is a tappet 13 which is adapted to be actuated when the cam is rotated. The gear end of the cam shaft 2 projects beyond the crank case A and in this instance is provided with a spherical ball 14, 100 105 110

the latter being formed with a socket 15 which is adapted to receive the end of the cam shaft 2, the ball being preferably provided with a collar 16 in which is mounted 5 a screw 17 whereby the ball may be locked upon the ends of the cam shaft as will be understood. Loosely mounted upon the ball 14 is the substantially semi-spherical socket 18 which has its apex provided with an eye 19. Secured to the rear end of the crank case A and extending longitudinally of the same is a bracket 20 which has its free end provided with a vertically disposed tooth segment 21. Pivotal secured to the bracket is the lower end of the actuating lever 22. The lever 22 is provided with an eye 23 in which is mounted one end of the link 24, the opposite end of the link being mounted in the eye 23, while the opposite 10 end of the link 24 is pivotally mounted within the eye 19 whereby upon movement of the lever 22 upon its pivot, the cam shaft 2 will be moved longitudinally within the crank case. To lock the lever in any desired 15 adjusted position, the lever is provided with a spring pressed pivoted thumb latch lever 25 to which is connected the rod 26, the lower end of the rod being engageable with the teeth of the segment 21 for locking the lever 22 in adjusted position. It will be apparent 20 that upon locking the thumb latch lever, the rod will be withdrawn against the tension of the spring from the teeth of the segment 21 thus permitting the lever to be rocked 25 upon its pivot to move the shaft longitudinally.

To temporarily break the ignition circuit when adjusting the cam 11 in reversing the rotation of the crank shaft the thumb latch 30 lever 29 is provided with extensions 27 which are normally engageable with the terminals 28 of the ignition circuit, the latter not being shown. It will be evident from this construction that when the lever 25 is 35 gripped to move the rod 26 to disengaging positions, the extension 27 which is in engagement with the terminals 28 under the action of the coil springs, the lever will be rocked upon its pivot to move the extension 40 into disengaging position with relation to the terminal whereby the ignition circuit 45 will be broken as will be understood.

From the foregoing description taken in connection with the accompanying drawings, it will be seen that when it is desired 50 to reverse the rotation of the crank shaft, by rocking the lever 22 upon its pivot, the shaft 2 will be moved longitudinally of the crank shaft thereby imparting a similar motion to the sleeve 9 thus causing the threads 55 to engage the walls of the grooves 12 of the cam and thereby partially rotating the cam axially of the cam shaft. It will be thus seen that the cam surface of the cam 11 will 60 be caused to engage the tappet 13 at the

different intervals thus actuating the valve of the gas engine to cause the reverse rotation of the crank shaft as will be understood. The forward portion 3 of the shaft will permit movement of the said shaft without 70 affecting the gear, thus motion may be imparted from the crank shaft to the cam shaft during any adjustment of the cam shaft. It will be further noted that owing to the connection between the cam and the cam shaft, 75 the cam may be moved in the path of an arc in either direction depending upon which direction the cam shaft is moved whereby any desired adjustment may be obtained for effecting the reversing of the engine as has been described. 80

Simultaneously with the movement of the lever 22, the lever 25 is rocked upon its pivot so as to cause the extension 27 to disengage the terminal 28 to effect a temporary breaking of the ignition without the liability of the gas within the cylinder exploding to cause contrary movement of the crank shaft. When the cam has been adjusted to the desired degree, the thumb latch lever 25 is of 90 course released whereby the spring will actuate the extension to move the same into contact with the terminal 28. Thus the circuit to the ignition system will be temporarily broken to permit the adjusting of the 95 cam.

It is thought from the foregoing taken in connection with the accompanying drawings that the construction and operation of our device will be apparent to those skilled in 100 the art and that minor changes in the size, shape, proportion and minor details of construction may be made without departing from the spirit and scope of the appended 105 claims.

What we claim is:—

1. A reversing mechanism for gas engines comprising a longitudinally movable cam shaft, manually operated means for moving the shaft longitudinally, a universal 110 joint connecting said shaft and said manually operated means, means for rotating the shaft, a sleeve keyed to the shaft, spirally arranged threads formed on the outer surface of the sleeve, and a cam having spirally 115 arranged grooves formed therein to receive said threads whereby upon longitudinal movement of the cam shaft, the cam will be rotated axially upon the shaft and a tappet engageable with said cam. 120

2. A reversing mechanism for gas engines, comprising a longitudinally movable cam shaft, a portion of said shaft being of angular formation, a gear mounted on said portion, means for moving the shaft longitudinally, means engageable with said gear for rotating said shaft, spaced bearings 125 circling the shaft, a sleeve keyed to the shaft and journaled within said bearings, spirally arranged threads formed on the outer

outer surface of said sleeve, a cam surrounding said sleeve at intervals between said bearings, the inner surface of said cam being formed with spirally arranged grooves which receive said threads and a tappet engageable with said cam.

3. A reversing mechanism for gas engines, comprising a longitudinally movable shaft, means for rotating the shaft, manually operated means for moving the shaft longitudinally, a cam mounted on the shaft, means interposed between the cam and the shaft for imparting an independent rotary motion to the cam upon the shaft upon lon-

gitudinal movement of the said shaft, a 15 spring pressed member carried by the manually operated means, and a terminal of an ignition circuit also carried by said manually operated shaft moving means and adapted to contact with the spring pressed 20 member; whereby, the ignition circuit will be broken in advance of the longitudinal movement of the cam shaft.

In testimony whereof we affix our signatures.

EDWARD J. DUGAN.
JOHN P. PANTE.
